FIG. 4
Inventor
Mauro DiMauro,

834/Henry G. Bartel
Attorney

UNITED STATES PATENT OFFICE

2,200,132

PRESSING TABLE

Mauro Di Mauro, Scranton, Pa., assignor of one-half to Sheldon Pell, Scranton, Pa.

Application May 16, 1939, Serial No. 274,063

5 Claims. (Cl. 38—107)

My invention relates to improvements in pressing tables and has to do, more particularly, with equipment employed in the pressing of apparel such as trousers, skirts, coats and the like, wherefore in the goods to be finished includes a tubular section or sections and must be "finished" on a platen commonly known as a pressing "buck."

In clothing factories particularly, such "bucks" commonly have the form of a hollow, steam-jacketed metal casting and are employed in conjunction with a very heavy steam-jacketed pressing iron weighing in the neighborhood of twenty pounds. In the pressing of a single pair of trousers upon bucks of such design, the operator 10 must use the iron five distinct times and, between each operation, it is necessary to lift the iron from the work, place it upon a nearby iron rest and, after the trouser material has been properly readjusted upon the buck and sponged, again lift the iron onto the work. Thus, it will be appreciated, the pressman must lift and transfer the iron from buck to rest, and vice versa, a total of ten times in the pressing of a single pair of trousers. That the occupation of 15 trousers-presser is characterized by a degree of fatigue approaching physical exhaustion at the end of an eight hour day is an accepted fact in the clothing industry.

It is a primary object of my invention to provide a novel pressing table construction which obviates such iron elevation and transfer; which, accordingly, vastly reduces fatigue of the operator employing such equipment; which speeds up production; and which yields a better-finished article.

Another, and corollary, disadvantage inherent to pressing table constructions of the type with which the present invention is concerned, is wear and roughening of the pressing iron. Quite naturally, as the operator becomes more and more fatigued toward the end of the day, the placing of the iron upon its stand becomes more and more precipitous. In a short time, the smoothing surface of the iron, as well as the supporting surface of the stand, becomes rough, and the quality of the work performable suffers. The iron must then be reground, and the expense of such reconditioning and eventual iron replacement becomes a cost factor in plant operation.

50 My invention has, for another object thereof, material reduction of such wear and tear.

Further objects, and objects relating to economies and details of construction and operation will more definitely appear from the detailed description to follow. In one instance, I accom-

plish the objects of my invention by the means and procedure set forth in the following specification. My invention is clearly defined by the appended claims. Structures constituting preferred embodiments of my invention are illustrated in the accompanying drawing, in which:

Figure 1 is a perspective view of a pressing table construction constituting a preferred embodiment of my invention;

Fig. 2 is a view of the same table in side-elevation, portions of the iron rest and buck base being depicted in cross section to illustrate details of construction therein;

Fig. 3 is a horizontal sectional view taken on the line 3—3 of Fig. 2 and diagrammatically depicting the limits of pivotal movement characterizing the buck illustrated in Figs. 1 and 2; and

Fig. 4 is a detail vertical sectional view of a slightly modified buck structure in which an annular series of ball bearings is employed in lieu of the rollers illustrated in Figs. 1 through 3.

Throughout the several figures, similar numerals of reference refer to similar parts.

In a broad sense, the basic concepts of my invention may be said to find embodiment in an apparatus for the hand-finishing of trousers, and like objects having a tubular section to be pressed, consisting of a stand having a horizontal top surface adapted to receive and support a conventional tailor's iron, a cantilever platen the extended arm of which is adapted to receive and support the tubular member to be pressed, means for mounting said stand and cantilever platen with their respective iron-receptive surfaces in a common horizontal plane, and guide means associated with said mounting means for selectively positioning said co-planar iron-receptive surfaces in either a relative position of approximate continuity or a relative position of wide spacing such as to permit facile application or removal of the tubular member to be pressed on said platen arm.

More specifically, reference is made to the preferred embodiment of my invention depicted in Figs. 1 through 3, wherein there is illustrated a table 10 supported upon conventional legs 11, adjacent the right extremity of which table is mounted an elevated stand 12 having a horizontal top surface 12a adapted to support a conventional tailor's iron 13 of the type heated by steam supplied through flexible inlet and outlet hose 14 and 15. The stand 12 is suitably cushioned upon the table 10 by an interposed block of wood or similar material. The rear and side margins of the portions 12a of the stand are up-

wardly flanged as shown at 12b and 12c, thereby preventing escape of the iron therefrom.

At the left end of the table 10 is disposed a mount 17 for the pressing buck 18, which mount 5 is pivotally assembled with a standard 19 extending upwardly from the floor upon which the legs 11 are carried. The two arms 17a, 17b of the mount 17 are suitably journaled about the standard 19 and dissociation of the mount with 10 respect to the standard 19 is precluded by a nut 19a threaded upon the upper end of the standard. To insure facile pivotability of the mount 17 with respect to the table 10, a flat metal plate 30 is secured to the table and between this plate 15 and the base of the mount 17 are provided a plurality of rollers 20 received in recessed portions in the base of the mount and assembled therewith by pin-like axles 21, drive-fitted into the base of the mount.

20 Upon the mount 17 is secured the pressing buck or cantilever platen 18 which is of hollow, steam-jacketed construction, well known in the art. Steam is supplied to the steam space within the platen by means of inlet and outlet pipes 22 25 and 23 suitably connected for supply by flexible steam hose members 24, 25. The mount 17, with its platen 18 is, thus, freely pivotable about the axis of the standard 19, and to permit such free pivotal motion a slight spacing exists between the 30 free end of the platen 18 and the adjacent forward edge of the iron rest portion 12a. More than this, it will be noted that the top surface of the platen 18 and the top surface of the iron rest portion 12a are disposed in the same horizontal plane, whereby the iron 13 may be freely slid from rest to platen, and from platen to rest, without interference from the spaced edges of these two members.

40 In the position illustrated in Figs. 1 and 2, it is obvious that a tubular object such as the leg of a pair of trousers could not be installed upon, nor removed from, the platen 18. However, as illustrated by dotted lines in Fig. 3, the mount 17 with its platen may be swung out of alignment with 45 the stand 12 to an extent sufficient to permit of such installation and removal of tubular articles of apparel. To insure alinement of the platen 18 with the stand 12, such as illustrated in Figs. 1 and 2, a stop member 26 is provided upon the 50 plate 20, limiting the extent to which the platen may be swung in a counterclockwise direction. A similar stop member 27 is provided at the opposite side of the standard 19 which limits the extent to which the platen may be swung in a clockwise 55 direction, and the thus-defined position is such as to insure clearance, between the free end of the platen 18 and the stand 12, such that the tubular article of apparel may be readily installed and removed from the platen arm. The stops 60 may, obviously, be of any form, but are preferably, as shown, simple abutments engageable with the base edge of the mount 17.

The operation of the thus described apparatus should be self-apparent. Through the simple expedient of drawing the arm 18 toward the operator to the limit of extent permitted by the stop 27, the trouser leg or similar tubular article may be slid upon the free end of the platen. After such installation of the tubular article, the platen is 65 pushed away from the operator until the stop 26 is abutted by the portion 17a of the mount, whereupon the iron 13 may be slid along the stand portion 12a, onto the platen 18 and upon the tubular piece of apparel (not shown). Upon completion of the pressing of that portion of the tu- 70

bular article which is disposed upon the top surface of the platen 18, the iron may be returned to the stand portion 12a, and the tubular article may be rotated upon the platen to bring a new portion thereof into disposition upon the top of 5 the platen. The iron may then be again slid along the horizontally aligned members 12a and 18. When the entire tubular article has been thus operated upon, the platen may be again swung toward the operator and the article may be removed with ease. It will be noted that the movement of the iron from its stand 12 to the platen 18 is a simple planar shifting, involving no requirement of lifting. The operator is, therefore, not subjected to the burden of lifting and 10 lowering the iron, and may devote substantially his entire energies to the pressing operation. More than this, the elimination of the requirement of lifting and lowering the heavy tailor's iron, which weighs in the neighborhood of twenty 15 pounds, results in less wear and tear of the iron, platen and stand surfaces—a condition characteristic of all prior art arrangements with which I am familiar and one which necessitates refinishing of the iron surface to remove irregularities and roughness developed therein. 20

I am aware that numerous changes in size, configuration, and structural design are possible without departing from the basic concepts of my invention. For example, the specific roller bearing pivot arrangement disclosed as a preferred embodiment of my invention may be dispensed with in favor of a ball bearing construction such as illustrated in Fig. 4, wherein the platen 118 is pivotally mounted upon the mounting member 117 by means of a bolt 128, and a multiplicity of ball bearings 120 are interposed between the platen and mount and arranged in annular races formed therein. Other variations of a similar nature will appear to those skilled in the art upon 40 familiarization with the concepts of my invention and I, therefore, claim my invention broadly, as indicated by the appended claims.

What I claim is:

1. In an apparatus for the hand-finishing of 45 trousers and like objects having a tubular section to be pressed: a table, a stand mounted upon said table having a horizontal top surface adapted to receive and support a conventional tailor's iron, a cantilever platen the extended arm of 50 which is adapted to receive and support the tubular member to be pressed, and means for securing said platen to said table and definitely maintaining the top surface of its extended arm in the horizontal plane of iron-support of said stand, said last-mentioned means including a vertical-pivot platen mount the vertical pivot-axis of which is spaced from the proximate edge of said iron stand a distance equal to the radial length of said extended platen arm enabling selective manual placement of said platen arm with its horizontally-maintained top surface in either a position of substantial continuity or a position of wide spacing with respect to the co-planar iron-supporting surface of said stand. 65

2. In an apparatus for the hand-finishing of trousers and like objects having a tubular section to be pressed: a stand having a horizontal top surface adapted to receive and support a conventional tailor's iron, a cantilever platen the extended arm of which is adapted to receive and support the tubular member to be pressed, and means for positively mounting said stand and cantilever platen with their respective iron-receptive surfaces maintained in a fixed common 70

horizontal plane, said last-mentioned means including positive guide means for enabling manual shifting of the relative position of said co-planar-maintained platen and stand such that the free end of said platen is selectively disposable in either a position of substantially contiguous continuity with said stand or a position of wide spacing with respect thereto.

3. In an apparatus for the hand-finishing of trousers and like objects having a tubular section to be pressed: a stand having a horizontal top surface adapted to receive and support a conventional tailor's iron, a cantilever platen the extended arm of which is adapted to receive and support the tubular member to be pressed, means for positively mounting said stand and cantilever platen with their respective iron-receptive surfaces maintained in a fixed common horizontal plane, said last-mentioned means including positive guide means for enabling manual shifting of the relative position of said co-planar-maintained platen and stand such that the free end of said platen is selectively disposable in either a position of substantially contiguous continuity with said stand or a position of wide spacing with respect thereto, and stop means defining said two selective positions recited.

4. In an apparatus for the hand-finishing of trousers and like objects having a tubular section to be pressed: a table, a stand mounted upon said table having a horizontal top surface adapted to receive and support a conventional tailor's iron, a cantilever platen the extended arm of which is adapted to receive and support the tubular member to be pressed, means for securing said platen to said table and definitely maintaining the top surface of its extended arm in the horizontal plane of iron support of said stand, said last-mentioned means including a vertical-pivot platen mount the vertical pivot-axis of which is spaced from the proximate edge of said

iron stand a distance equal to the radial length of said extended platen arm enabling selective manual placement of said platen arm with its horizontally-maintained top surface in either a position of substantial continuity or a position of wide spacing with respect to the co-planar iron-supporting surface of said stand, and stop means for positively defining said position of substantial continuity during performance of the pressing operation.

5. In an apparatus for the hand-finishing of trousers and like objects having a tubular section to be pressed: a table, a stand mounted upon said table having a horizontal top surface adapted to receive and support a conventional tailor's iron, a steam chambered cantilever platen the extended arm of which is adapted to receive and support the tubular member to be pressed, means for securing said platen to said table and definitely maintaining the top surface of its extended arm in the horizontal plane of iron support of said stand, said last-mentioned means including a vertical-pivot platen mounting the vertical pivot-axis of which is spaced from the proximate edge of said iron stand a distance equal to the radial length of said extended platen arm enabling selective manual placement of said platen arm with its horizontally-maintained top surface in either a position of substantial continuity or a position of wide spacing with respect to the co-planar iron-supporting surface of said stand, and stop means for positively defining the position of substantial continuity of platen and iron stand and positively limiting the extent of swing of said steam-supply-coupled platen arm.

MAURO DI MAURO.
